UNITED STATES PATENT OFFICE.

JAMES M. WRIGHT, OF KEOKUK, IOWA.

LOCK.

1,113,858.

Specification of Letters Patent.

Patented Oct. 13, 1914.

Application filed August 8, 1912. Serial No. 714,132.

To all whom it may concern:

Be it known that I, JAMES M. WRIGHT, a citizen of the United States of America, residing at Keokuk, in the county of Lee, 5 Iowa, have invented certain new and useful Improvements in Locks, of which the following is a specification.

The present invention appertains generally to locks, and aims to provide a novel 10 and improved device of that character.

One of the objects of the present invention is to provide a lock including a tumbler bolt of novel construction, in order that it may be manipulated to projected and retracted 15 positions by means of a proper key, the tumbler bolt and lock case having coöperating means for holding the tumbler bolt in either of said positions.

Another object of the present invention 20 is to provide a device of the nature indicated, wherein a plurality of the tumbler bolts may be employed in order that the respective tumbler bolts may be independently actuated by suitable selective keys, and in 25 order that all of the tumbler bolts may be simultaneously operated by a master key.

A further object of the present invention 30 is to provide a lock which will be simple and inexpensive in construction as well as simple and efficient in its use.

With the foregoing and general objects outlined and with other objects in view, which will be apparent as the nature of the invention is better understood, the present 35 invention resides in the combination and arrangement of parts and in the details of construction hereinafter described and claimed, it being understood that changes in the precise embodiment of the invention 40 herein disclosed can be made within the scope of what is claimed without departing from the spirit of the invention.

The invention has been illustrated in its preferred embodiments in the accompanying 45 drawings, wherein:

Figure 1 is a fragmental side elevation of a lock constructed in accordance with the present invention, with the near side plate removed. Fig. 2 is a sectional view thereof taken on the line $x-x$ of Fig. 1. Figs. 3 and 4 are fragmental perspective views of the talon portions of the tumbler bolts. Fig. 5 is a view similar to Figs. 3 and 4, illustrating a slight modification. Fig. 6 is a 55 side elevation of a modified form of lock, the near side plate being removed. Figs.

7, 8 and 9 are fragmental side elevations of the keys for manipulating the tumbler bolts.

In Figs. 1 and 2 there is illustrated, a lock case 1 which may be of the mortise type, to be adapted to fit within a mortise formed in the edge of a door, or the like. Disposed between the side plates of the case 1 are a pair of lock bolts 2 which are disposed snugly side by side and which have their heads or outer ends engaging loosely through the face of the case, in order to mount the lock bolts to allow sliding and oscillatory movements, the tails or inner ends of the bolts being adapted to be swung vertically. Each of the bolts 2 is provided with an H-shaped gate forming opening 3 intermediate its ends, the openings 3 of the bolts registering with each other and having a fence pin or lug 4 passing therethrough, the lug or pin 4 being attached to one or both side plates of the case. Although the inner ends or tails of the lock bolts will fall by gravity, the depression of the bolts is facilitated by means of a leaf spring or springs 5 disposed above the bolts and carried by lugs 6 formed on the interior of the case, the free end or ends of the spring or springs 5 bearing upon the backs or upper edges of the bolts to depress them. Each of the lock bolts is provided with a lower recess or notch adjoining its tail or inner end, and forming a talon having the curved walls 14 and 15. Each of the bolts is also provided with a transverse bore 10 directly above the talon, and which opens into the talon. The bore 10 forms a key gap or seat lying within the sweep of the key bit and arranged to engage the free end of the key bit. The walls or shoulders 14-15 of each talon are connected by a web 9.

In Fig. 9, there is illustrated a master key, which has a bit a of a width approximately equal to the aggregate thickness of the lock bolts, and which is provided with notches or clefts in its free corners to engage the webs of the bolts.

In Figs. 7 and 8 are illustrated a pair of companion or mate selective keys, each of which embodies a half bit b or c , respectively, which are adapted to operate the respective lock bolts. Each bit b and c has a single notch or cleft.

In practice, when the lock bolts are retracted, the upper outer notches formed by the openings 3 are engaged over the fence

lug or pin 4, so as to ordinarily prevent the lock bolts from being shot or projected, the spring or springs serving to retain the lock bolts in depressed position. When the master key is inserted into the proper key hole provided in the side of the case, and when the key is swung or rotated, the free end of the bit will move or sweep along the curved line indicated by dotted line 8 in Fig. 1, the inner or rear talon walls 14 being so curved as to permit the bit to swing into the talons and to engage the key gaps provided by the bores 10, the notches of the bit α engaging the respective webs 9. Then, when the bit of the key is turned over the axis of the shank of the key, the notches of the bit will engage the webs 9, to cause the inner ends of the lock bolts to be swung upwardly, as indicated by the dotted line 18 in Fig. 1, and the bit engaging within the key gaps or sockets 10 will cause the bolts to be shot or projected outwardly, the webs 9 and notches of the key bit being of such proportions that the bolts will just be lifted sufficiently to permit the central contracted portions or gates of the openings 3 to pass over the fence lug or pin 4. When the key has been completely rotated, so as to be withdrawn from the case, the bolts will be projected so as to engage the keeper (not shown) of the door jamb, the upper inner notches provided by the openings 3 engaging over the fence lug or pin to prevent the bolts from being accidentally retracted or disengaged from the keeper. When either of the supplemental or selective keys is inserted into the case, the same will only serve to manipulate one of the bolts in the manner above indicated. Thus, the supplemental keys may be given to two different persons, in order that the successive insertions of the two supplemental keys will be necessary to shoot or retract both of the bolts, as will be apparent. The advantages of such an arrangement will be clearly obvious, it being noted that both of the lock bolts may be simultaneously operated by means of the master key, without the assistance of the supplemental keys.

It will be apparent that any number of the improved tumbler bolts may be employed in one lock, in order that the several bolts may be actuated by independent selective keys, and in order that all of the bolts may be actuated simultaneously by a master key. If desired, a single lock bolt may be employed, which necessitates the use of only a single key.

The H-shaped openings 3 are of such proportions, that when the inner ends or tails of the lock bolts are raised by the notches of the key bits engaging the webs 9, the central contracted portions or gates of the openings 3 will align with the fence lug or pin 4, to permit the bolts to be shot or retracted. This prevents the lock bolts from

being operated by false keys, inasmuch as the insufficient or excessive upward or downward movement of the lock bolts, would prevent them from being slid outwardly and inwardly, as will be apparent.

A number of key changes may be provided by positioning the webs 9 at various points between the sides of the respective lock bolts, and by increasing and decreasing the proportions of the webs and notches of the key bits. Thus, as illustrated in Fig. 5, the web 9 may be disposed intermediate the sides of the lock bolts, the webs of the lock bolts illustrated in Fig. 2, being disposed at the outer sides of the lock bolts, although they may be disposed on the inner sides or at various intermediate positions. The variations in the webs will also necessitate corresponding changes in the notches of the key bits. The dotted line 11 in Fig. 3 illustrates how the web 9 may be cut away, and the dotted lines 12 illustrate how the web may be extended, to necessitate various keys. It will also be apparent that the webs 9 may be of various thicknesses, they being of less thickness than the thickness of the lock bolts.

In the form illustrated in Fig. 6, the case 1 is of such construction, as to be secured to the side or face of a door, the inner end or tail 17 of the lock bolt being extended through a vertically elongated slot provided in the back of the case, to permit the proper oscillation or vertical movement of the lock bolt. Otherwise, the modified form embodies general features above discussed.

Having thus described the invention, what is claimed as new is:—

1. In a lock, a bolt, means for mounting the same for sliding and oscillatory movements and for locking the same against sliding movements unless swung to a predetermined position, the bolt having a talon provided with a key gap, and a web connecting the talon walls, in combination with a key having a bit arranged to engage the key gap for imparting a sliding movement to the bolt, and having a cleft to engage the web for swinging the bolt to sliding position.

2. In a lock, a case including a face plate, a lock bolt mounted for sliding and oscillatory movements through the face plate, means for locking the bolt against sliding movements unless swung to a predetermined position, the lock bolt having a talon provided with a key gap and a web connecting the talon walls, in combination with a key having a bit arranged to engage the key gap for imparting a sliding movement to the bolt, and having a cleft to engage the said web for swinging the bolt to sliding position.

3. In a lock, a plurality of juxtaposed bolts, means for mounting the same for slid-

ing and oscillatory movements and for locking the same against sliding movements unless swung to predetermined positions, each bolt having a talon provided with a
5 key gap, and a web connecting the talon walls, in combination with a master key having a bit arranged to engage the key gaps of all the bolts to impart a sliding movement to the bolts, and selective keys
10 each having a bit arranged to engage the key gap of one bolt, the key bits having clefts to engage the webs of the respective bolts for swinging the bolts to sliding positions.
15 4. In a lock, a case including a face plate, a plurality of lock bolts arranged side by side and mounted for sliding and oscillatory movements through the face plate, means for locking the bolts against sliding movements unless swung to predetermined positions, each bolt having a talon provided with a key gap, and a web connecting the talon walls, in combination with a master key having a bit arranged to engage the
20 key gaps of all the bolts to impart a sliding movement to the bolts, and selective keys each having a bit arranged to engage

the key gap of one bolt to impart a sliding movement thereto, the key bits having clefts to engage the respective webs for swinging 30 the bolts to sliding positions.

5. In a lock, a case, a bolt therein, means for mounting the bolt for sliding and oscillatory movements, and including a coöperating fence and gate carried by the case and 35 bolt, the fence and gate locking the bolt against sliding movements unless swung to a predetermined position, the bolt having a talon provided with a key gap and a web connecting the talon walls, the web being 40 narrower than the bolt and being disposed between the sides thereof, in combination with a key having a bit arranged to engage the key gap of the bolt for imparting a sliding movement to the bolt and having a 45 cleft arranged to engage the said web for swinging the bolt to sliding position.

In testimony whereof I have hereunto set my hand in presence of two subscribing witnesses.

JAMES M. WRIGHT.
